UNITED STATES PATENT OFFICE.

ABNER JUDSON LURRY, OF NEW ORLEANS, LOUISIANA.

DRIER.

Application filed January 26, 1928. Serial No. 249,717.

The present invention relates to improvements in driers, and more particularly refers to a drier useful when drying woven, braided or twisted fabrics, such as cloth, yarn, rope etc. 5 Such material requires drying after being saturated with dye or wax compounds, and it is an object of the invention to provide a compact and simple form of drier for receiving and containing at the same time a great 10 linear amount of such material, whereby the entire amount may be subjected at once to the drying atmosphere within the drying chamber.

Other objects of the invention are to provide 15 an improved form of cellular drying chamber, to secure an active circulation of hot air or other drying medium throughout all the cells of the chamber, and to provide an improved driving mechanism for the web 20 supporting rollers and the blast fan.

With the foregoing and other objects in view, the invention will be more fully described hereinafter, and will be more particularly pointed out in the claims appended 25 hereto.

In the drawings, wherein like symbols refer to like or corresponding parts throughout the several views,

Figure 1 is a top plan view, with parts 30 broken away, and the driving belts omitted, of an apparatus constructed in accordance with the present invention.

Figure 2 is a longitudinal section taken vertically through the apparatus.

Figure 3 is a fragmentary side elevation showing the arrangement for driving the rollers.

Figure 4 is a cross section taken on the line 4-4 in Figure 2, and

Figure 5 is a similar view taken on the line 5-5 also in Figure 2.

Referring more particularly to the drawings 6 designates the top of the drying chamber, 7 the bottom, 8 and 9 the end walls and 45 10 and 11 the side walls thereof. This drying chamber may be of any suitable form and of appropriate length, height and width to accommodate a quantity of the material to be formed which is shown in the form of a 50 web 12. This web is received into the drying chamber at the lower portion of the end wall 8 as shown in Figure 2, feed rollers 13 and 14 being provided to receive the web.

Thereafter, the web is passed into the chamber 55 and circulated in a number of superposed runs or traverses, and each traverse being

stepped upwardly until the upper portion of the drying chamber is reached, from which the web is conveyed off at the upper portion of the opposite end wall 9, the web carried 60 about the rollers 15 and 16 and thence to its destination. Near the end wall 8 are the idler rolls 17 arranged in a substantially vertical bank to receive the web 12 at this end. In a similar way adjacent the opposite end wall 9 65 is a substantially vertical bank of drive rollers 18, the shafts of which are extended upon the exterior side wall 11, as shown in Figure 3, where they are provided with the pairs of friction wheels 18' disposed in engagement 70 with the endless drive belt 19. Between the pairs of friction wheels 18' may be placed tension or pressure rolls 20 engaging the belt 19 at the opposite side. The upper end of the belt is engaged about a pulley 21 on a 75 counter shaft 22 mounted in bearings 23 upon the upper portion of the drying chamber or other support.

The intermediate portions of the web 12 are supported at appropriate points by banks 80 of rollers or supporting rods 24 and 25, as shown in Figure 2. These supports may be provided at appropriate intervals in order to support the web 12 without sagging, it being understood that the web is subjected to 85 a suitable degree of tension to maintain it in a flat and stretched condition within the drying chamber. The web is carried alternately from one drive roller 18 to the next highest idler roller 17; thence back across the 90 drying chamber to the next highest driving roller 18. In this way a great linear amount of the web can be at one time contained within the drying chamber and subjected to the drying action of the atmosphere of the chamber. 95

Drying air or other medium is circulated to the drying chamber by means of the fan 26 shown in Figures 1 and 2. The eye of the fan communicates directly with the surrounding atmosphere or by conduit 26' with the top of the drying chamber, while the exhaust of the fan is connected by a trunk 27 with a heating box 28 located above the intermediate portion of the drying chamber and extending transversely there-across with its 100 opposite ends communicating with lateral flues 29 and 30, shown in Figure 4. In the box 28 is a steam or other heating coil or element 31 provided to raise the temperature of the air supplied thereto by the fan.

In the side walls 10 and 11 are provided inlet ports 32 and 33 leading into the cells of

the chamber between the horizontal partitions 34. The ports 32 and 33 may be provided with the dampers or baffles 36 in order to control the amount of the hot air circulated to any particular cell.

Opposite end portions of the drying chamber are provided with outlet flues 37 and 38, as shown in Figure 5. These outlet flues are similar to the inlet flues and they communicate with the various superposed cells of the container through the outlet ports 39 and 40. The outlet flues open at their upper ends directly to the atmosphere. The ports 39 and 40 may be controlled by appropriate dampers or baffles 41.

The fan may be driven by an electric or other motor 42, shown in Figures 1 and 2. This motor is provided with a pulley 43 engaged by the drive belt 44, which extends about a driven pulley 45 on the shaft 46. A second pulley 47 on this shaft is arranged to receive a belt 48, which is also engaged with the pulley 49 upon the fan shaft. The drive shaft 46 also fixedly carries a small pulley 50, over which is trained the belt 51 for engaging the larger driven pulley 52 on the counter shaft 22. A belt tightener is indicated at 53.

The drying is done gradually through as many stages, or steps as there may be cells provided, which admits a method of obtaining rapid and thorough drying with low temperature and minimum energy. The rollers 13 and 14 may supply a certain tension or resistance to the free movement of the material 12 and thus enable the material to be stretched by speeding up the means for withdrawing the opposite end of the material. The web or material 12 traverses the lowermost cell four times, more or less; then passes upward into the succeeding cell and repeats, until it finally passes out of the uppermost cell in and about the rollers 15 and 16 which supply sufficient frictional draft to withdraw the material at a constant rate of speed. These rollers 15 and 16 may be geared together and driven by a belt 54 from the counter shaft or from other movable part.

The air, as shown by the arrows in Figure 4 enters at the two ends of the uppermost cell and may be made to similarly enter both ends of the subjacent cells. The blast flows parallel to and between the traverses of passing material, forming cross sprays. The blasts meet at the cross-wise center of the cells and then such blast travels parallel to the surface of the drying material to the ends of the cells, where the saturated air escapes to the atmosphere through the four exhaust flues 37 and 38.

Natural air is applied to the final stage of drying to neutralize the temperature and harden any wax application for direct baling or storage of the finished material.

The machine will be found particularly adapted for drying canvas when treated with wax compounds for the tent and tarpaulin industry, but, of course, will be applicable to other long goods. The arrows show cold air entering through the ends of the upper cell and to the fan, therefore upper cell is entirely closed to all flues. To convert the next lower cell to cold air all of its flue connections are closed and air (as above) admitted through its ends, passing to the fan through 35.

It is obvious that various changes and modifications may be made in the details of construction and design of the above specifically described embodiment of this invention without departing from the spirit thereof, such changes and modifications being restricted only by the scope of the following claims.

What is claimed is:—

1. A drier comprising a drying chamber having outlets for saturated gas at opposite ends and inlets for drying medium at opposite sides of its central portion, a cellular interior structure within the chamber, means to movably support a web to be dried throughout the cells, means for driving said last-named means, and means to supply the drying medium to said inlets.

2. A drier comprising a drying chamber having outlets for saturated gas at opposite ends and inlets for drying medium at opposite sides of its central portion, a cellular interior structure within the chamber, means to movably support a web to be dried throughout the cells, means for driving said last-named means, a heating box communicating with the inlets, and means to force gas through the heating box and subsequently through the inlets.

3. A drier comprising a drying chamber having outlets for saturated gas at opposite ends and inlets for drying medium at opposite sides of its central portion, a cellular interior structure within the chamber, means to movably support a web to be dried throughout the cells, means for driving said last-named means, a heating box communicating with the inlets, a heater within said heating box, means for circulating a gas to said heating box against the heater therein and subsequently to said inlets, and dampers in the cells of the chamber to control the entrance of the heated gas.

4. A drier comprising a drying chamber having outlets for saturated gas at the end portions thereof and inlets for drying medium at the sides of the central portion, a cellular interior structure within the chamber, means to movably support material to be dried throughout the cells, means for driving said last-named means, and means to supply drying medium to said inlets.

ABNER JUDSON LURRY.
